A. A. REINKE

Des. 78,985

RUG

Filed March 25, 1929

Inventor:

Armin A. Reinke

By George C. Cook.

Attorney

UNITED STATES PATENT OFFICE.

ARMIN A. REINKE, OF OSHKOSH, WISCONSIN, ASSIGNOR TO WAITE CARPET COMPANY, OF OSHKOSH, WISCONSIN, A CORPORATION OF WISCONSIN.

DESIGN FOR A RUG.

Application filed March 25, 1929. Serial No. 30,604. Term of patent 3½ years.

To all whom it may concern:

Be it known that I, ARMIN A. REINKE, a citizen of the United States, residing at Oshkosh, in the county of Winnebago and State of Wisconsin, have invented a new, original, and ornamental Design for Rugs, of which the following is a specification, reference being had to the accompanying drawing, forming part thereof.

The figure is a plan view of a rug showing my new design.

I claim:

The ornamental design for a rug as shown.

ARMIN A. REINKE.
